MAGAZINE THROAT FOR FIREARMS

Frederick L. Humeston, Orange, Conn., assignor of one-half to The High Standard Manufacturing Corporation, Hamden, Conn., a corporation of Connecticut, and one-half to Sears, Roebuck and Co., Chicago, Ill., a corporation of Illinois

Application September 15, 1948, Serial No. 49,313

10 Claims. (Cl. 42—17)

1

The present invention relates in general to firearms and more especially to improvements in repeating firearms of the tubular-magazine type.

An object of the invention is to provide superior means for transferring cartridges successively from the tubular magazine of a repeating firearm into position for introduction into the cartridge-chamber thereof.

A further object of the invention is to provide a repeating tubular-magazine firearm with a superior magazine-throat which is instrumental in transferring cartridges from the tubular magazine of the firearm into position for introduction into the cartridge-chamber thereof and which is effective also as cartridge-restraining means for preventing a cartridge from moving upwardly in the magazine-throat when the breech-bolt is in breech-closing position.

A still further object of the invention is to provide a repeating tubular-magazine firearm with an improved magazine-throat which embodies complementary cartridge-restraining elements movable laterally with respect to each other and operable by the breech-bolt to prevent a cartridge from tilting upwardly in the magazine-throat when the breech-bolt is in breech-closing position and to release a cartridge in the magazine-throat when the breech-bolt is moved rearwardly out of breech-closing position.

With the above and other objects in view, as will appear to those skilled in the art from the present disclosures, this invention includes all features in the said disclosure which are novel over the prior art.

In the accompanying drawings, in which certain modes of carrying out the present invention are shown for illustrative purposes:

Fig. 1 is a vertical elevation in section of the receiver of a repeating firearm of the tubular-magazine type in which in which the present invention is incorporated and includes a fragmentary portion of the stock, barrel and tubular magazine;

Fig. 2 is a view corresponding to Fig. 1 but illustrating the position which the parts assume after the firearm has been discharged and the breech-bolt unlocked and partially retracted;

Fig. 3 is a view corresponding to Figs. 1 and 2 but illustrating the position which the parts assume when the breech-bolt is in its fully-retracted position in the receiver;

Fig. 4 is a broken top plan view, with a fragmentary portion of the breech-bolt in horizontal section, of the trigger-plate of the firearm when

the parts thereof are in the positions shown in Fig. 1, the cartridge-follower of the tubular magazine being indicated by broken lines;

Fig. 5 is a view corresponding to Fig. 4 but illustrating the positions which the parts assume when the breech-bolt is partially retracted, as shown in Fig. 2;

Fig. 6 is an end elevation in section of the receiver and trigger-plate assembly of the firearm on line 6—6 of Fig. 1;

Fig. 7 is an end elevation in section of the receiver and trigger-plate assembly on section line 7—7 of Fig. 2;

Fig. 8 is a perspective view looking at the outer face of one separable throat-member of the longitudinally-split magazine-throat of the firearm;

Fig. 9 is a perspective view of the separable throat-member of Fig. 8 looking at the inside face thereof, provided with a cartridge-guide passage and cartridge-restraining lip; and

Fig. 10 is a perspective view of the cartridge-elevator of the magazine-throat.

The particular firearm shown in the drawings for the purpose of illustrating one embodiment of the invention is a repeating firearm of the slide-action type and comprises, in the main, a receiver 15 having a barrel 16 secured in the forward end thereof. A buttstock 17 is secured to the rear end of the receiver by fastening-means indicated by the screw 18. A substantially-rectangular recess is formed vertically in the underside of the receiver to provide an action-chamber 20 which is coaxial with the cartridge-chamber 21 of the barrel 16 and superposed over an aperture 22 adapted to accommodate the trigger-plate 23 of the firearm, the receiver and trigger-plate assembly being hereinafter referred to as the "frame" of the firearm.

A breech-bolt 24 is movably mounted in the action-chamber 20 and supported for reciprocal movement therein on the upper edges of the trigger-plate 23. A cartridge-ejection port 25 is provided in the right-hand side wall of the receiver, while the underside of the top wall 26 thereof is formed with a notch 27 having a forwardly-and-upwardly-inclined breech-bolt locking-shoulder 28. Suitably secured to the barrel is a tubular magazine 29, the latter underlying the barrel, and having a friction fit at its rear end in a counterbored aperture 30 in the front wall of the receiver. As indicated in Figs. 1, 2 and 3, the tubular magazine 29 is of approved construction common to repeating firearms of this type and, as shown,

includes an inner tube 31 in which is housed a spring 32 adapted to urge a cartridge-follower 33 rearwardly in the magazine for automatically feeding cartridges from the tubular magazine to the cartridge-chamber 21 of the barrel, as and in the manner hereinafter described.

The breech-bolt 24 is adapted to be reciprocated manually in the action-chamber 20 of the frame by means of slide-mechanism including a fore-end (not shown) having an action-slide bar 34 guided for reciprocable movement in an aperture in the front wall of the receiver and provided at its rear end with a laterally offset cam-lug 35 adapted to cammingly engage in a cam-recess 36 which is of similar geometric shape and intersects the lower left-hand edge of the breech-bolt whereby forward and rearward movements of the action-slide bar impart similar movements to the breech-bolt for locking and unlocking the latter in breech-closing position. To these ends, the top side of the breech-bolt is provided at its rear end with an upwardly-and-rearwardly-sloping heel 37 adapted to be swung up into engagement with the shoulder 28 on the underside of the top wall 26 of the receiver by coaction of the cam-lug 35 of the action-slide bar with the cam-recess 36 of the breech-bolt as the action-slide is moved forwardly relative to the barrel-unit to lock the breech-bolt in breech-closing position; and to be swung downwardly out of engagement with the locking-shoulder 28 of the receiver by coaction of the cam-lug 35 of the action-slide bar with the cam-recess 36 of the breech-bolt as the action-slide bar is moved rearwardly relative to the barrel-unit to thereby open the breech and extract and eject a spent shell from the ejection-port of the receiver.

Further details of the breech-bolt include a vertical aperture 38 extending longitudinally along the underside thereof and providing clearance adjacent the rear end of the bolt for the fire-control mechanism, including the spring-actuated hammer 39 pivotally mounted in the trigger-plate 23; and clearance adjacent the forward end of the bolt for the improved magazine-throat of this invention. In this connection, the forward portion of the longitudinal aperture 38 is formed with a central rib 40 depending from the top wall thereof and having a downwardly-and-rearwardly-sloping cam-surface 41 at its rear end for actuating the cartridge-elevator 42 of the magazine-throat, as hereinafter described.

By referring to Fig. 1, it will be seen that the cam-surface 41 of the breech-bolt rib also serves as a stop which temporarily holds the cartridge A in the magazine-throat from moving to its rearmost position therein.

At this point it seems fitting to point out that it is this engagement of the rim or head of the cartridge A with the underside of the breech-bolt, and more particularly the rib thereof, together with the characteristic downward-swinging movement of the rear end of the breech-bolt in unlocking the latter from the locking-notch of the receiver which gives rise to the need for the improved cartridge-restraining means of this invention in order to positively hold the cartridge A in the magazine-throat from moving upwardly therein prior to unlocking and moving the breech-bolt rearwardly in the receiver. It has been found that when the cartridge A is unrestrained it may readily be tilted up into the upper part of the magazine-throat by careless handling of the firearm, thereby releasing the next-succeeding cartridge B which would move rearwardly into

the magazine-throat beneath the cartridge A. Consequently, when the action-slide is actuated to unlock the breech-bolt the initial downward-swinging movement of the rear-end portion 5 thereof would force the upper cartridge A downwardly in the magazine-throat, thereby jamming the cartridge against the cartridge B directly below. As a result, it might be found that it was impossible to open the breech-bolt or that one or both of the cartridges would be damaged so as to prevent satisfactory operation of the fire-arm.

Other details of the breech-bolt and fire-control mechanism of the firearm are ancillary to 15 a complete disclosure of the invention and hence are omitted, it being sufficient to point out that the fire-control mechanism, including the hammer 39 and trigger 43, is of any suitable construction mounted in the rear portion of the trigger-plate, while the magazine-throat of this invention is secured in a vertical recess 45 in the forward end of the trigger-plate.

The magazine-throat is indicated generally at 46 in Figs. 1, 2 and 3, and is adapted to receive 25 cartridges, which are fed thereto from the rear end of the tubular magazine 29 by the spring-pressed follower 33, and to transfer the cartridges successively up into the path of the forwardly-moving breech-bolt for movement thereby 30 into the cartridge-chamber of the barrel.

The aforementioned cartridge-elevator 42 of the magazine-throat is a blade-like member (see Fig. 10) adapted to be pivoted as at 47 between opposite sides of the frame for vertical movement in the recess 45 of the trigger-plate, and 35 comprises a rearwardly-extending reach 48 having an upwardly-projecting breech-bolt engaging-lug 49 thereon; and a forwardly-extending reach 50 having a sector-shaped front end 51 constituting a cartridge cut-off. Formed on the upper edge of the forward reach 50 of the cartridge-elevator and forwardly of the pivot-pin 47 thereof, is a second upwardly-projecting breech-bolt engaging-lug 52. The underside of the elevator 45 has an underslung belly-portion 53 provided with a pin 54 which projects transversely therefrom forwardly of the pivot-pin 47 of the elevator. The end of the pin 54 constitutes a 50 stop projecting laterally from the left-hand side of the elevator for the purpose as will hereinafter appear. The belly-portion 53 of the elevator is engaged by the forwardly-extending substantially-U-shaped reach 55 of an elevator spring 56. The latter is secured at its rear end by a 55 pin 51 in the vertical recess 45 of the trigger-plate and has a lower reach 58 extending forwardly from the spring 56 and adapted to engage against the bottom of the vertical recess 45 of the trigger-plate whereby the upper reach of the spring exerts a constant force on the underside of the cartridge-elevator forwardly of its pivot-pin 47, to elevate the forwardly-extending reach 50 thereof upwardly in the magazine-throat.

In accordance with this construction, as the 60 breech-bolt is moved forwardly into breech-closing position, the rib 40 on the underside thereof, and more especially its cam-surface 41, will engage the forward breech-bolt engaging-lug 52 of the cartridge-elevator, thereby pivoting the elevator downwardly in the magazine-throat against the resistance of the elevator-spring 56. Thus, the front end or cartridge cut-off 51 of the elevator will be displaced below the path of movement of cartridges being fed from the tubular magazine and hence will permit a cartridge to

be moved from the magazine by the spring-urged follower 33 into the magazine-throat. Where there is more than one cartridge in the magazine, the cartridge A which is in the magazine-throat constitutes, in effect, a temporary cut-off for the next-succeeding cartridge B which, as shown in Fig. 1, is held by the first cartridge A with its rear end extending part way into the magazine-throat. On unlocking the breech-bolt, so as to open the cartridge chamber and extract a fired cartridge, the rear end-portion of the breech-bolt will be swung downwardly, whereupon the cam-surface 41 of the breech-bolt rib 40 forces the cartridge A downwardly and forwardly. However, shortly after the breech-bolt begins to move rearwardly, the cartridge A is released, as will hereinafter appear, whereupon the force of the compressed elevator-spring 56 moves the elevator upwardly in the magazine-throat, as shown in Fig. 2, thereby elevating the cartridge A therein upwardly into the upper part of the throat to assume, ultimately, the position shown in Fig. 3, wherein the rear end of the cartridge A is immediately in front of the front face of the breech-bolt, the forward end of the cartridge A being held in an elevated position with respect thereto, by the forward end of the elevator. Simultaneously, the cartridge cut-off 51 of the elevator moves into the path of the next-succeeding cartridge B being delivered from the magazine-tube, thereby to stop the cartridge B in the position shown in Figs. 2 and 3. Then, as the breech-bolt is returned into breech-closing position, the cartridge A in the upper part of the magazine-throat is engaged by the forwardly-moving breech-bolt and moved into the cartridge-chamber of the barrel. At substantially the same time the cartridge A is being chambered, the forward breech-bolt engaging-lug 52 of the cartridge-elevator is engaged by the cam-surface 41 of the breech-bolt rib, whereupon the elevator is pivoted downwardly against the resistance of its spring 56, its cartridge cut-off 51 being lowered out of the path of the cartridge B so as to permit the latter to move rearwardly out of the magazine into the magazine-throat. At this point it may be pointed out that the rearwardly-extending reach of the cartridge-elevator, and more particularly the breech-bolt engaging-lug 49 thereof, is provided so that in the event the elevator-spring 46 should have insufficient force to raise the forward reach of the elevator during the rearward excursion of the breech-bolt, the breech-bolt engaging-lug 49 at the rear end of the elevator will be positively engaged by the underside of the rearwardly-moving breech-bolt to positively lift the forward end of the cartridge-elevator.

The construction of the improved magazine-throat of this invention is concerned primarily with means for effectively holding a cartridge in the magazine-throat 46 from being moved or tilted upwardly therein by indiscretionary use of the firearm when the breech-bolt is in breech-closing position, as shown in Fig. 1, in which event the next-succeeding cartridge in the magazine would be released prematurely and cause the cartridges to jam in the magazine-throat when the breech-bolt is unlocked, as hereinabove described. To prevent this circumstance, the magazine-throat comprises two separable substantially-complementary throat-members 60 and 61 respectively, which in the preferred construction comprise die-cast metal blanks embodying substantially-rectangular body-portions 62 and

63 respectively, provided with rearwardly-extending reaches 64 and 65 having transverse apertures 66 and 67 adapted to receive opposite ends respectively of the pin 47 of the cartridge-elevator, which serve to secure the rearwardly-extending reaches of the respective separable throat-members of the magazine-throat in the vertical recess 45 of the trigger-plate. In this connection, the aperture 66 of the right-hand throat-member 60 is of slightly greater diameter than the diameter of the pin 47, whereby the right-hand throat-member 60 fits loosely on the pin and hence is capable of limited pivotal or rocking-movement laterally to and from the left-hand throat-member 61 for the purpose hereinafter described. Extending forwardly from the forward edges of the body-portions of the separable throat-members 60 and 61 are integral semicylindrical collar-portions 68 and 69 respectively, the forward edges of which are adapted to abut against the rear end of the tubular magazine when the magazine-throat is assembled in the recess of the trigger-plate. Depending from the forward ends of the body-portions of the separable throat-members are integral tongue-portions 70 and 71 respectively, having transverse axially-aligned apertures 72 and 73 adapted to receive a pin 74 for securing the forward ends of the separable throat-members in the aforesaid recess of the trigger-plate. Again, the aperture 72 in the tongue 70 of the right-hand throat-member is made of sufficiently greater diameter than the diameter of the pin 74 so as to form a loose fit thereon and hence permit the right-hand throat-member to move or rock laterally to and from the left-hand throat-member.

The body-portions 62 and 63 of the separable throat-members 60 and 61 embody integral relatively-thin side walls 75 and 76 respectively, extending upwardly substantially vertically therefrom, the outer faces of the side walls being in the vertical planes of the corresponding outer faces of the throat-members, while the inner faces of the respective side walls are laterally offset outwardly with respect to the inner faces of the relatively-thick body-portions of the respective throat-members, as shown in Figs. 6 and 7. Formed on the inner faces of the throat-members are longitudinal grooves 77 and 78 respectively. The grooves constitute substantially-cylindrical surfaces of a revolution which intersect, at their forward ends, the semicylindrical collar-portions 68 and 69 respectively of the throat-members and extend upwardly and rearwardly therefrom. The portion of each groove which intersects the inner face of the relatively-thick body-portion of its respective throat-member is relatively deep and substantially-quadrant-shaped in cross section, whereas the intersection of each groove with the laterally-offset relatively-thin side wall of its respective throat-member is relatively shallow, the upper longitudinal edge of each shallow groove constituting a relatively-narrow shoulder. These shoulders of the respective throat-members are hereinafter referred to as the "cartridge-restraining lips" 79 and 80 thereof respectively. Moreover, the grooves 77 and 78 blend at their rear ends into relatively-shallow substantially-rectangular clearance-recesses 81 and 82 milled or otherwise formed in the inner faces of the rear-end portions of their respective throat-members. The clearance-recesses extend upwardly to form longitudinally-extending shoulders 83 and 84 immediately be-

low the upper edges of the respective side walls 75 and 76, and forwardly to intersect the bottom edges of substantially-V-shaped notches 85 and 86 formed therein, each clearance-recess, and its respective-V-shaped notch, being provided for permitting the rim of a cartridge to move upwardly in the magazine-throat when the cartridge is engaged and moved forwardly therein by the breech-bolt, as hereinafter described. In addition to the aforesaid groove and clearance-recess formed in the inner face of each throat-member, a relief-cut is formed vertically therein and more particularly in the inner face of the body-portion of each throat-member. Each relief-cut is indicated at 87 and 88 respectively and extends from the tongue-portion of its respective throat-member rearwardly to the rear end of the reach thereof, the relief-cut 88 in the left-hand throat-member being substantially parallel to the inner face of its throat-member, whereas the relief-cut 87 in the inner face of the right-hand throat-member makes a slight angle with respect thereto such that the depth of the relief-cut is slightly greater at its forward end than at its rear end.

Now when the separable throat-members, together with the cartridge-elevator, are assembled in the vertical aperture 45 of the trigger-plate by means of the aforesaid pins 47 and 74, the elevator constitutes a separator which holds the oppositely-disposed throat-members loosely in substantially-parallel relationship and slightly spaced apart at their forward ends, as indicated clearly in Fig. 5. The oppositely-disposed relief-cuts 87 and 88 of the respective throat-members provide a slot for the vertical movement of the elevator therebetween, the slight taper given to the relief-cut 87 of the right-hand throat-member providing freedom for movement of the latter laterally with respect to the elevator and the left-hand throat-member, the latter condition being assured by the aforementioned loose fits which the pins 47 and 74 make in the corresponding apertures of the right-hand throat-member.

The oppositely - disposed complementary grooves 77 and 78 of the respective throat-members provide a continuous cartridge-passage which extends from the semi-circular collars 68 and 69 at the forward ends of the respective throat-members rearwardly to the complementary clearance-recesses 81 and 82, the transverse dimension of the cartridge-passage being at all times slightly greater than the rim diameter of a cartridge so as to enable a cartridge to move freely longitudinally therethrough from the magazine of the firearm. Moreover, when the separable throat-members are in substantially-spaced-parallel relationship, the cartridge-restraining lips 79 and 80 respectively of the cartridge-passage are spaced apart laterally a distance sufficient to permit the body of a cartridge to be moved upwardly out of the cartridge-passage by the elevator. On the other hand, when the right-hand throat-member is displaced laterally inwardly toward the left-hand throat-member, the aforesaid lips 79 and 80 of the cartridge-passage are moved together so that the distance therebetween is less than the diameter of the body-portion of a cartridge in the cartridge-passage, the lips thereby constituting stop-means for positively holding or restraining the cartridge from moving or tilting upwardly out of the magazine-throat.

The latter circumstance is one which it is

desirable to achieve at the time the breech-bolt is in breech-closing position so as to prevent the next-succeeding cartridge in a magazine from becoming jammed with the cartridge already in the magazine-throat and, to this end, the side wall 75 of the right-hand throat-member 60 is provided, on its outer face and adjacent its forward end, with a cam-lug 89 joined integrally or otherwise secured thereto, and arranged to lie in the path of a portion of the breech-bolt, as shown clearly in Fig. 5, so that when the latter is moved into breech-closing position, a portion of the breech-bolt will engage the cam-lug 89 and cam the right-hand throat-member inwardly laterally relative to the left-hand throat-member, thereby diminishing the lateral spacing of the cartridge-restraining lips 79 and 80 of the cartridge-passage so as to positively hold the cartridge therein from moving or tilting upwardly. This condition prevails as long as the breech-bolt is in breech-closing position and also while the heel 37 of the breech-bolt is being swung downwardly out of locking engagement with the locking-notch 27 in the top-wall 26 of the receiver. However, shortly after the breech-bolt begins to move rearwardly out of breech-closing position, it disengages the cam-lug 89 of the right-hand throat-member, and the latter, being free to move laterally, is readily displaced outwardly by the force of the spring-actuated cartridge-elevator 42 acting to lift a cartridge in the cartridge-passage of the magazine and to position its cut-off 51 in the path of the cartridge being fed from the magazine. As a consequence of the outward movement of the right-hand throat-member, the cartridge-restraining lips 79 and 80 of the magazine-throat are opened outwardly, thereby permitting the cartridge in the cartridge-passage to move upwardly into the upper part thereof. By way of example only, a preferred construction provides for a lateral displacement of the right-hand throat-member of substantially 0.030 inch, so that the lateral spacing of the cartridge-restraining lips 79 and 80 is substantially 0.025 inch less than the diameter of the body of a cartridge when the breech-bolt is in breech-closing position, while the lateral spacing of the cartridge-restraining lips is substantially 0.005 inch greater than the diameter of the cartridge-body when the breech-bolt is out of breech-closing position.

Although in the exemplary embodiment of the invention, the right-hand throat-member of the magazine-throat has been described as being movable laterally with respect to the left-hand throat-member, it will be appreciated that the left-hand throat-member may be constructed to move relative to the right-hand throat-member of the magazine-throat; or that both the right- and left-hand throat-members thereof may be moved to and from each other. Moreover, although the achievement of appreciable rocking movement of one throat-member with respect to the other by means of loosely fitting parts is a highly satisfactory means for carrying out the invention, it will be appreciated that the construction of the separable throat-members may be such that one member may be flexed with respect to the other, or both members may be flexed with respect to each other. Consequently, in referring to the movement of one member with respect to the other, the term "move" as used hereinafter and in the claims shall be understood to connote flexure as well as pivotal or rocking movement.

The operation of the firearm, and more particularly the improved cartridge-restraining means of the magazine-throat, is believed to be clear from the foregoing description, but may be described in brief as follows. Assume that the breech-bolt is in its breech-closing position, as shown in Fig. 1, with a cartridge in the cartridge-chamber of the barrel and a cartridge A in the magazine-throat. Under these conditions, a portion of the bolt is in engagement with the cam-lug of the right-hand throat-member whereby its cartridge-restraining lip is held closely adjacent the complementary lip of the opposite throat-member so as to effectively hold the cartridge A from moving or tilting upwardly in the magazine-throat. On pulling the trigger 43 of the fire-control mechanism to release the hammer 39, the cartridge in the barrel 16 of the firearm is discharged. Thereupon, the operator pulls rearwardly on the fore-end of the action-slide bar 34, thereby pulling the rear end, and in particular the heel 37 of the breech-bolt, downwardly out of engagement with the shoulder 28 in the underside of the top wall 26 of the receiver so as to unlock the breech-bolt from the receiver, the breech-bolt pivoting about its lower forward corner in a counterclockwise direction, as seen in Fig. 1. As the breech-bolt swings downwardly, the cam-surface 41 of its rib 40 forces the cartridge A forward and downwardly slightly, but as soon as the breech-bolt disengages the locking shoulder 28 and begins its rearward movement, the cam-lug 89 of the right-hand throat-member is released to permit the right-hand throat-member to be moved outwardly laterally by the force of the spring-actuated elevator acting to move the cartridge A upwardly therein, whereupon the cartridge-restraining lips of the throat-member are spread apart and permit the cartridge A to be moved upwardly therein by the elevator 42 into engagement with the cartridge-stop 90 at the rear end of the magazine-throat, as shown in Fig. 2. Simultaneously, the next-succeeding cartridge B is moved rearwardly into engagement with the cartridge cut-off 51 of the elevator.

When the breech-bolt reaches the end of its rearward excursion in the receiver, the elevator will have raised the cartridge A into the position shown in Fig. 3, wherein the rim or head of the cartridge is immediately in front of the front face of the breech-bolt. Consequently, as the latter moves forwardly, the cartridge A is engaged and moved forwardly thereby, the rim of the cartridge moving forwardly through the complementary clearance-recesses 81 and 82 at the rear ends of the respective side walls of the throat-members into the V-shaped notches thereof, whereupon the rim of the cartridge swings upwardly into axial alignment with the breech-bolt. As the breech-bolt approaches its breech-closing position, the said breech-bolt will re-engage the cam-lug 89 to move the right-hand throat-member inwardly and the cam surface 41 of the breech-bolt engages the lug 52 of the elevator to lower the forward end of the latter and in particular the cartridge cut-off 51 thereof, out of the path of the next-succeeding cartridge B which is immediately moved by the spring-urged follower 33 of the tubular magazine into the magazine-throat. After the breech-bolt has been swung upwardly into locking position in the receiver, the lug 52 of the elevator will be disengaged, whereupon the elevator-spring will urge the forward end of the elevator upwardly. How-

ever, the latter is unable to elevate the cartridge B in the magazine-throat since the breech-bolt has again engaged the cam-lug 89 of the right-hand throat-member to move the cartridge-restraining lips of the magazine-throat together to effectively prevent the cartridge in the throat from moving upwardly therein while the breech-bolt is in breech-closing position. The elements of the firearm, including the magazine-throat, are again in position for firing the next-succeeding cartridge.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A tubular magazine repeating firearm, including in combination: a frame; a barrel mounted in said frame and having a cartridge-chamber; a tubular magazine associated with said barrel and located below the cartridge-chamber therein; a magazine-throat supported in said frame between said tubular magazine and said cartridge-chamber, said magazine-throat comprising two separable complementary throat-members one of which is movable bodily laterally with respect to the other; a breech-bolt reciprocably mounted in said frame for movement to and from breech-closing position, said breech-bolt having means arranged to engage a portion of the one throat-member of said magazine-throat when said breech-bolt is moved into breech-closing position to move said one throat-member bodily toward the complementary throat-member of said throat thereby to positively hold a cartridge from moving upwardly therein, said breech-bolt means being arranged to disengage the said one throat-member of said magazine-throat when said breech-bolt is moved rearwardly in said frame, thereby to enable said one throat-member to move bodily away from the complementary throat-member of said throat and release the cartridge therein; and a cartridge-elevator pivotally mounted in said frame and actuated by said breech-bolt to move upwardly substantially vertically between said separable throat-members, said cartridge-elevator being constructed and arranged to urge a cartridge therebetween upwardly, thereby displacing said one throat-member outwardly bodily with respect to the complementary throat-member to release the said cartridge from said magazine-throat and transfer it upwardly into said cartridge-chamber.
2. A tubular magazine repeating firearm, including in combination: a frame; a barrel mounted in said frame and having a cartridge-chamber; a tubular magazine associated with said barrel and located below the cartridge-chamber therein; a magazine-throat supported in said frame between said tubular magazine and said cartridge-chamber, said magazine-throat comprising two separable complementary throat-members one of which is movable bodily laterally with respect to the other; a projection on the one throat-member of said throat; a breech-bolt reciprocably mounted in said frame for movement to and from breech-closing position, said breech-bolt being constructed and arranged to engage the projection of said one throat-member of said

magazine-throat when said breech-bolt is moved into breech-closing position to move said one throat-member bodily toward the complementary throat-member of said throat thereby to positively hold a cartridge from moving upwardly therein, said breech-bolt being constructed and arranged to engage the projection of the said one throat-member of said magazine-throat when said breech-bolt is moved rearwardly in said frame thereby to enable said one throat-member to move bodily away from the complementary-member of said throat and release the cartridge therein; and a cartridge-elevator pivotally mounted in said frame and actuated by said breech-bolt to move upwardly substantially vertically between said separable throat-members, said cartridge-elevator being constructed and arranged to urge a cartridge therebetween upwardly, thereby displacing said one throat-member outwardly bodily with respect to the complementary throat-member to release the said cartridge from said magazine-throat and transfer it upwardly into said cartridge-chamber.

3. A tubular magazine repeating firearm, including in combination: a frame; a barrel mounted in said frame and having a cartridge-chamber; a tubular magazine associated with said barrel and located below the cartridge-chamber therein; a magazine-throat supported in said frame between said tubular magazine and said cartridge-chamber, said magazine-throat comprising two separable throat-members one of which is movable bodily laterally with respect to the other and provided with a cartridge-restraining element; a breech-bolt reciprocably mounted in said frame for movement to and from breech-closing position, said breech-bolt having means constructed and arranged to engage a portion of the one separable throat-member of said magazine-throat when said breech-bolt is moved into breech-closing position to move the said one separable throat-member and its cartridge-restraining element bodily toward the other separable throat-member of said throat thereby to positively hold a cartridge from moving upwardly therein, said breech-bolt means being constructed and arranged to disengage the said one separable throat-member of said magazine-throat when said breech-bolt is moved rearwardly in said frame thereby to enable the said one separable throat-member and its cartridge-restraining element bodily to move bodily away from the other separable throat-member of said throat and release the cartridge therein; and a cartridge-elevator pivotally mounted in said frame and actuated by said breech-bolt to move upwardly substantially vertically between said separable throat-members, said cartridge-elevator being constructed and arranged to urge a cartridge therebetween upwardly, thereby displacing said one throat-member outwardly bodily with respect to the complementary throat-member to release the said cartridge from said magazine-throat and transfer it upwardly into said cartridge-chamber.

4. A tubular magazine repeating firearm, including in combination: a frame; a barrel mounted in said frame and having a cartridge-chamber; a tubular magazine associated with said barrel and located below the cartridge-chamber therein; a magazine-throat supported in said frame between said tubular magazine and said cartridge-chamber, said magazine-throat comprising two separable throat-members, one of

said separable throat-members being movable bodily laterally with respect to the other and provided with a cartridge-restraining element and a lateral projection; a breech-bolt reciprocably mounted in said frame for movement to and from breech-closing position, said breech-bolt being constructed and arranged to engage the projection on the one separable throat-member of said magazine-throat when said breech-bolt is moved into breech-closing position to move the said one separable throat-member and its cartridge-restraining element bodily toward the other separable throat-member of said throat thereby to positively hold a cartridge from moving upwardly therein, said breech-bolt being constructed and arranged to disengage the projection of the one separable throat-member of said magazine-throat when said breech-bolt is moved rearwardly in said frame thereby to enable the said one separable throat-member and its cartridge-restraining element bodily to move away from the other separable throat-member of said throat and release the cartridge therein; and a cartridge-elevator pivotally mounted in said frame and actuated by said breech-bolt to move upwardly substantially vertically between said separable throat-members, said cartridge-elevator being constructed and arranged to urge a cartridge therebetween upwardly, thereby displacing said one throat-member outwardly bodily with respect to the complementary throat-member to release the said cartridge from said magazine-throat and transfer it upwardly into said cartridge-chamber.

5. A tubular magazine repeating firearm, including in combination: a frame; a barrel mounted in said frame and having a cartridge-chamber; a tubular magazine associated with said barrel and located below the cartridge-chamber therein; a magazine-throat supported in said frame between said tubular magazine and said cartridge-chamber, said magazine-throat being split longitudinally to form two separable throat-members movable bodily laterally with respect to each other, each throat-member being provided with a semicylindrical cartridge-guide groove on its inner face, the guide-groove of one throat-member being constructed and arranged to complement the guide-groove of the other throat-member to form a passage for a cartridge delivered thereto from said magazine; a breech-bolt mounted in said frame for movement to and from breech-closing position, said breech-bolt having means constructed and arranged to engage a portion of one separable throat-member of said magazine-throat when said breech-bolt is moved into breech-closing position to move said one separable throat-member bodily laterally with respect to the other separable throat-member of said throat thereby to constrict the cartridge-passage therein so as to positively hold a cartridge from moving upwardly in said throat, said breech-bolt means being constructed and arranged to disengage the said one separable throat-member of said magazine-throat when said breech-bolt is moved rearwardly in said frame thereby to enable said one separable throat-member to move bodily away from the other separable throat-member of said throat and release the cartridge in the constricted passage thereof; and a cartridge-elevator pivotally mounted in said frame and actuated by said breech-bolt to move upwardly substantially vertically between said separable throat-members, said cartridge-elevator being constructed and

arranged to urge a cartridge therebetween upwardly, thereby displacing said one throat-member outwardly bodily with respect to the complementary throat-member to release the said cartridge from said magazine-throat and transfer it upwardly into said cartridge-chamber.

6. A tubular magazine repeating firearm, including in combination: a frame; a barrel mounted in said receiver and having a cartridge-chamber; a tubular magazine associated with said barrel and located below the cartridge-chamber therein; a magazine-throat supported in said frame between said tubular magazine and said cartridge-chamber, said magazine-throat being split longitudinally to form two separable throat-members, each throat-member being provided with a semicylindrical cartridge-guide groove on its inner face, the guide-groove of one throat-member being constructed and arranged to complement the guide-groove of the other throat-member to form a passage for a cartridge delivered thereto from said magazine; pivotal-means constructed and arranged to support said separable throat-members of said magazine-throat in said frame for bodily movement laterally with respect to each other; a breech-bolt mounted in said frame for movement to and from breech-closing position, said breech-bolt having means constructed and arranged to engage a portion of one separable throat-member of said magazine-throat when said breech-bolt is moved into breech-closing position to move said one separable throat-member bodily laterally with respect to the other separable throat-member of said throat thereby to constrict the cartridge-passage therein so as to positively hold a cartridge from moving upwardly in said throat, said breech-bolt means being constructed and arranged to disengage the said one separable throat-member of said magazine-throat when said breech-bolt is moved rearwardly in said frame thereby to enable said one separable throat-member to move bodily away from the other separable throat-member of said throat and release the cartridge in the constricted passage thereof; and a cartridge-elevator pivotally mounted in said frame and actuated by said breech-bolt to move upwardly substantially vertically between said separable throat-members, said cartridge-elevator being constructed and arranged to urge a cartridge therebetween upwardly, thereby displacing said one throat-member outwardly bodily with respect to the complementary throat-member to release the said cartridge from said magazine-throat and transfer it upwardly into said cartridge-chamber.

7. A tubular magazine repeating firearm, including in combination: a frame; a barrel mounted in said frame and having a cartridge-chamber; a tubular magazine associated with said barrel and located below the cartridge-chamber therein; a magazine-throat supported in said frame between said tubular magazine and said cartridge-chamber, said magazine-throat being split longitudinally to form two separable throat-members each provided with a semicylindrical cartridge-guide groove on its inner face, the guide-groove of one throat-member being constructed and arranged to complement the guide-groove of the other throat-member to form a passage for a cartridge delivered thereto from said magazine; a cam-lug extending laterally from the outer face of one of said separable throat-members; means arranged to support said separable throat-members loosely in said frame

for bodily movement laterally with respect to each other; a breech-bolt mounted in said frame for movement to and from breech-closing position, the said breech-bolt having a projection constructed and arranged to engage said cam-lug of the said one separable throat-member of said magazine-throat when said breech-bolt is moved into breech-closing position to move said one separable throat-member bodily laterally with respect to the other separable throat-member of said magazine-throat thereby to constrict the passage therebetween and positively hold a cartridge from moving upwardly therein, the said breech-bolt projection being constructed and arranged to disengage the cam-lug of said one separable throat-member when said breech-bolt is moved rearwardly in said frame thereby to enable said one separable throat member to move bodily away from the other separable throat-member of said throat and release the cartridge in the passage thereof; and a cartridge-elevator pivotally mounted in said frame and actuated by said breech-bolt to move upwardly substantially vertically between said separable throat-members, said cartridge-elevator being constructed and arranged to urge a cartridge therebetween upwardly, thereby displacing said one throat-member outwardly bodily with respect to the complementary throat-member to release the said cartridge from said magazine-throat and transfer it upwardly into said cartridge-chamber.

8. A tubular magazine repeating firearm, including in combination: a frame; a barrel mounted in said frame and having a cartridge-chamber; a tubular magazine associated with said barrel and located below the cartridge-chamber therein; a magazine-throat supported in said frame between said tubular magazine and said cartridge-chamber, said magazine-throat comprising two separable throat-members movable bodily laterally with respect to each other, each having a semi-tubular portion at its forward end, an upwardly-projecting side-panel intermediate its semi-tubular portion and its rear end, and a guide-groove on the inner face of its respective side-panel, the said semi-tubular portion, side-panel, and guide-groove of the one separable throat-member of said magazine-throat being constructed and arranged to complement the corresponding semi-tubular portion, side-panel and guide-groove of the other throat-member; a breech-bolt reciprocably mounted in said frame for movement to and from breech-closing position therein, said breech-bolt having means constructed and arranged to engage a portion of one of said separable throat-members of said magazine-throat when said breech-bolt is moved into breech-closing position to move the said one separable throat-member including its semi-tubular portion, side-panel and guide groove bodily laterally into complementary relationship with the corresponding parts of the second separable throat-member of said throat thereby to positively hold a cartridge from tilting upwardly therein, said breech-bolt means being constructed and arranged to disengage the said one separable throat-member of said magazine-throat when said breech-bolt is moved rearwardly in said frame thereby to enable the said one separable throat-member including its semi-tubular portion, side-panel and guide-groove to move bodily away from the corresponding parts of the other separable throat-member of said throat and release the cartridge therein; and a cartridge-elevator pivotally mounted in said frame and

actuated by said breech-bolt to move upwardly substantially vertically between said separable throat-members, said cartridge-elevator being constructed and arranged to urge a cartridge therebetween upwardly, thereby displacing said one throat-member outwardly bodily with respect to the complementary throat-member to release the said cartridge from said magazine-throat and transfer it upwardly into said cartridge-chamber.

9. A tubular magazine repeating firearm, including in combination: a frame; a barrel mounted in said frame and having a cartridge-chamber; a tubular magazine associated with said barrel and located below the cartridge-chamber therein; a magazine-throat supported in said frame between said tubular magazine and said cartridge-chamber, said magazine-throat comprising two separable throat-members movable laterally with respect to each other, each having a semi-tubular portion at its forward end, an upwardly-projecting side-panel intermediate its semi-tubular portion and its rear end, and a guide-groove on the inner face of its respective side-panel, the said semi-tubular portion, side-panel, and guide-groove of the one separable throat-member of said magazine-throat being constructed and arranged to complement the corresponding semi-tubular portion, side-panel and guide-groove of the other throat-member; a projection on the side-panel of the one separable throat-member; a breech-bolt reciprocably mounted in said frame for movement to and from breech-closing position therein, said breech-bolt being constructed and arranged to engage the projection of the said one separable throat-member of said magazine-throat when said breech-bolt is moved into breech-closing position to move the said one separable throat-member including its semi-tubular portion, side-panel and guide-groove bodily laterally into complementary relationship with the corresponding parts of the second throat-member of said throat thereby to positively hold a cartridge from tilting upwardly therein, said breech-bolt being constructed and arranged to disengage the projection of said one separable throat-member of said magazine-throat when said breech-bolt is moved rearwardly in said frame thereby to enable the said one separable throat-member including its semi-tubular portion, side-panel and guide-groove to move bodily away from the corresponding parts of the other separable throat-member of said throat and release the cartridge therein; and a cartridge-elevator pivotally mounted in said frame and actuated by said breech-bolt to move upwardly substantially vertically between said separable throat-members, said cartridge-elevator being constructed and arranged to urge a cartridge therebetween upwardly, thereby displacing said one throat-member outwardly bodily with respect to the complementary throat-member to release the said cartridge from said magazine-throat and transfer it upwardly into said cartridge-chamber.

10. A tubular magazine repeating firearm, including in combination: a frame; a barrel mounted in said frame and having a cartridge-chamber; a tubular magazine associated with

said barrel and located below the cartridge-chamber therein; a magazine-throat supported in said frame between said tubular magazine and said cartridge-chamber, said magazine-throat comprising two separable throat-members movable laterally with respect to each other, each having a semi-tubular portion at its forward end, an upwardly-projecting side-panel intermediate its semi-tubular portion and its rear end, and a guide-groove, the latter being formed on the inner face of its respective side-panel and provided with a cartridge-restraining lip at its upper edge, the said semi-tubular portion, side-panel, guide-groove and cartridge-restraining lip of the one separable throat-member of said magazine-throat being constructed and arranged to complement the corresponding semi-tubular portion, side-panel, guide-groove and cartridge-restraining lip of the other throat-member; a projection comprising a cam-surface extending outwardly laterally from the outer face of said one separable throat-member of said magazine-throat; a breech-bolt reciprocably mounted in said receiver for movement to and from breech-closing position therein, said breech-bolt having a portion constructed and arranged to engage the cam-surface of said one separable throat-member of said magazine-throat when said breech-bolt is moved into breech-closing position to move the said one separable throat-member including its semi-tubular portion, side-panel, guide-groove and cartridge-restraining lip bodily laterally into complementary relationship with the corresponding parts of the second throat-member of said throat whereby said complementary cartridge-engaging lips coact to positively hold a cartridge from tilting upwardly therein, said breech-bolt portion being constructed and arranged to disengage the cam-surface of said one separable throat-member of said magazine-throat when said breech-bolt is moved rearwardly in said frame thereby to enable the said one separable throat-member including its semi-tubular portion, side-panel, guide-groove and cartridge-restraining lip thereof to move bodily away from the corresponding parts of the other separable throat-member of said throat and release the cartridge therein; and a cartridge-elevator pivotally mounted in said frame and actuated by said breech-bolt to move upwardly substantially vertically between said separable throat-members, said cartridge-elevator being constructed and arranged to urge a cartridge therebetween upwardly, thereby displacing said one throat-member outwardly bodily with respect to the complementary throat-member to release the said cartridge from said magazine-throat and transfer it upwardly into said cartridge-chamber.

FREDERICK L. HUMESTON.
